his Attorneys.

UNITED STATES PATENT OFFICE

JAMES E. VINCENT, OF JOHNSTOWN, PENNSYLVANIA

BLOWPIPE

Application filed March 1, 1929. Serial No. 343,647.

This invention relates to blowpipes such as are employed in the art of cutting with gases, and more particularly to a blowpipe which is especially adapted for the efficient combustion and use of natural gas at the standard low pressure at which natural gas is commercially furnished.

Heretofore, with blowpipes of the class to which this invention belongs, it has been necessary to materially boost the pressure of natural gas in order to use such gas, thus entailing extra expense and labor. The blowpipe of the present invention is designed to use natural gas at the standard commercial pressure of from eight to nine ounces.

Another and important object is to provide an integral key for locking the inner and outer tips against rotation, this feature having the dual advantage of being an integral part of the tip and therefore fixed against misplacement, and also being an integral part of the tip it is formed of the same metal as the tip and has the same rate of expansion and contraction as the tip and, therefore, will not bind.

In the drawings:

Figure 1 is a vertical sectional view through the head and top of a blowpipe embodying my invention.

Figure 2 is a side elevation of the inner tip member.

Figure 3 is a transverse section taken on the line III—III of Figure 1.

Figure 4 is a transverse section taken on the line IV—IV of Figure 1.

Referring more particularly to the drawings, the numeral 1 designates the head of the blowpipe, said head being provided with a neck 2 having in the upper portion thereof a branched passageway 3 communicating at its forward end with a chamber 4, an upwardly inclined passageway 5 and a second upwardly inclined passageway 6. Communicating with the rear or receiving ends of the passageways 3, 5 and 6 are the pipes 7, 8 and 9 which serve to conduct cutting oxygen, preheating oxygen, and combustible gas, respectively, thereto. The upper end of the passageway 5 communicates with a chamber 10 formed by a bore extending downwardly

and forwardly into said head and having threaded therein the body 11 of an injector, the said injector having a stem 12 mounted in said chamber and an operating head 13, there being packing 14 interposed between said head and seat 15 on top of the head. This injector is provided with a central bore 16, the upper end of which communicates by lateral ports 17 with the chamber 10. The lower end of the injector is adapted to discharge centrally into an inclined passageway 18 which in turn discharges into an annular chamber 19 provided in the lower portion of the blowpipe head and surrounding the inner tip member, to be described hereinafter. The passageway 6 discharges into a chamber 20 surrounding the lower end of the said injector and communicating with the passageway 18.

Extending downwardly from the chamber 4 is a short passageway 21, which merges with an enlarged threaded bore 22 extending to the chamber 19.

Threaded into the said bore 22 is an inner tip member, indicated generally at 23. This member comprises an upper threaded portion 24 cooperating with the thread in the bore 22 and is provided with a rounded head 25 adapted to seat against the rounded upper end of said bore.

The tip 23 is cut away intermediate its ends to provide a portion 36' of reduced diameter which cooperates with the outer tip member 32 to form a mixing chamber 36 of over half the length of the outer tip member 32.

The inner tip member 23 is provided with a plurality of relatively large V-shaped grooves 27 extending longitudinally from the threaded portion 24 to the cut-away portion 36'. The grooves 27 are of such size that their cross-sectional area is at least equal to half the cross-sectional area of the mixing chamber 36.

The portion 28 of the tip 23 below the mixing chamber 36 is tapered to correspond to the tapered nose of the outer tip 32 and is provided with V-shaped grooves 37 through which the mixture of gases from the mixing chamber 36 pass. The inner tip 23 is provided with a central bore 30 for conducting cut-

ting oxygen from the chamber 4 to the central outlet orifice 31.

The outer tip member 32 fits within the lower end of the head 1 and surrounds the lower portion of the inner tip member 23. This outer tip member has a cylindrical upper portion 33 adapted to fit within the lower end of the head and to fit snugly about the cylindrical body of the inner tip 23, thus sealing the outer sides of the grooves 27. For the purpose of securing the two members together an integral key projection 34 is provided on the inner surface of the outer member 32 and a key-way 35 is formed in the inner tip member. This manner of connecting the inner and outer tip members has proved of great advantage in the quick and efficient assembling of said members. Also by providing an integral key, there is no chance of the key becoming lost, and the key being formed of the same material as the tips the expansion and contraction of the key and key-way will be the same and, therefore, the key will not be loosened nor will it bind as is often the case when the keys are composed of different metals.

It will be noted that the lower end of the outer tip member projects beyond the lower end of the inner tip member, thereby providing a frusto-conical chamber 38. This chamber 38 has been found to be of great benefit in that it provides for the use of gases of high igniting point without danger of blowing out the flame through the pressure of the oxygen delivered through the orifice 31, since it shields the preheating flame from drafts or currents of air induced by the jets and flowing longitudinally of the blowpipe. Furthermore, this chamber serves to preheat the oxygen, thereby producing a more intense heat than would be otherwise possible.

A leak-proof joint is provided between the head and the outer tip member by means of a gland nut 39 threaded upon the lower end of such head and comprising a packing 40 compressed into the joint between such head and tip.

In operation, oxygen for preheating purposes and the combustible gas having been turned on, the oxygen delivered through the injector will thoroughly commingle with the combustible gas in the passageway 18 and the chamber 19 and will be delivered through the grooves 27 into the chamber 36 where they will be further mixed, and the mixture will then pass through the grooves 37 into the chamber 38. The metal will be quickly preheated and at a substantially single spot, after which cutting oxygen will be supplied from the chamber 4 and the passageway 30 and will operate to cut or soften the metal.

While I have shown and described one specific embodiment of my invention it will be understood that I do not wish to be limited thereto, since various modifications may be

made without departing from the scope thereof, as defined in the appended claim.

I claim:

A blow pipe of the character described comprising a head, a tip carried by said head and comprising an inner tip member having a central passageway for cutting oxygen, an outer tip member surrounding said inner tip member, said inner tip member having a materially reduced diameter for more than half of its length within said outer tip member so as to form a mixing chamber of material size, a plurality of V-shaped grooves in the portion of said inner tip member above said reduced diameter portion, the combined cross-sectional area of said V-shaped grooves being at least half of the cross-sectional area of the space formed by said reduced diameter portion and said grooves extending from above said outer tip member into said space formed by said reduced diameter portion, and the lower end of said inner tip member below said reduced diameter portion being also provided with a plurality of V-shaped grooves for the passage of the mixture of gases from said mixing chamber, and means for supplying cutting oxygen to the central passageway in said inner tip and a mixture of preheating oxygen and a combustible gas to the V-shaped grooves in said inner tip.

In testimony whereof, I have hereunto set my hand.

JAMES E. VINCENT.
